UNITED STATES PATENT OFFICE.

THOMAS J. DUNN, OF JERSEY CITY, NEW JERSEY.

TELEGRAPH-TRANSMITTER.

No. 923,083.

Specification of Letters Patent. Patented May 26, 1908.

Application filed December 31, 1908. Serial No. 470,238.

To all whom it may concern:

Be it known that I, THOMAS J. DUNN, a citizen of the United States, residing at Jersey City, in the county of Hudson and State of New Jersey, have invented certain new and useful Improvements in Telegraphic Transmitters, of which the following is a full, clear, and exact description.

This invention relates to so-called semi-automatic telegraph keys, and has for its object to provide a simple and compact instrument which can be manufactured at low cost and which shall be thoroughly reliable in operation.

To this and other ends the invention consists in the novel features of construction and combinations of elements hereinafter described, and more particularly set forth in the claims.

A convenient and effective embodiment of my invention is illustrated in the annexed drawing, and referring now thereto, Figure 1 is a plan view with the casing in section, showing the operative parts. Fig. 2 is a section on line 2—2. Fig. 3 is a section on line 3—3. Fig. 4 is a detail view of the finger key end of the instrument, with one of the finger keys removed.

The operative parts of the device are mounted on a base A, preferably rectangular in form and made of cast metal, heavy enough to rest firmly on a table or desk, provided with feet a of soft rubber or other similar material. Around the base is an upwardly extending flange A' within which fits the inclosing casing or cover hereinafter described. At one corner of the base is a short upright post B having a downwardly extending slot in its top in which is securely fixed a horizontally extending blade-spring C, carrying at its forward end a stiff rod C'. On the rod is a slidable weight c provided with a set-screw c' by which it can be firmly secured in adjusted position. It will now be evident that if the rod or vibrator C' be drawn to one side, thus slightly flexing the spring C, and then be released, the vibrator will oscillate rapidly under the influence of its own momentum and the resiliency of the blade spring.

Slidably mounted on the vibrator is a collar C" provided with a set-screw c" by which it may be secured in adjusted position, and carrying a light flexible contact spring C³, said contact spring being U-shaped, as shown, and fastened to the collar by one end. The

opposite end of the contact spring lies adjacent to a fixed contact D, in the form of a screw working in a short vertical post d so as to be adjusted toward and from the spring. It will now be seen that as the vibrator oscillates the contact spring will at each inward movement impinge upon the contact screw D, and at each outward excursion will be withdrawn from contact therewith.

Near the free end of the vibrator is a low transversely arranged bracket E, in which are mounted three vertically reciprocatory plungers F, G, H, normally held in elevated position by coil springs f, g, h, respectively. The lower ends of these plungers extend through apertures in the base A and are guided thereby in their vertical movements. The plungers are tubular and at their upper ends are provided with longitudinal slots to receive feathers i on the stems of the finger buttons f', g', h', when said stems are inserted in the plungers.

The center plunger G carries a cam member G' having an inclined cam surface or edge g" arranged to bear on the underside of the vibrator C' when the said plunger and cam member are in their uppermost positions, the action of the cam member being to hold the vibrator to the right (as viewed in Fig. 3) of its central position, with the spring C slightly flexed. It will therefore be seen that on depression of the plunger G the cam member will be carried out of engagement with the vibrator, whereupon the tension of spring C will throw the vibrator to the other side, after which it continues to oscillate by its own momentum and the resiliency of the spring, as previously described.

Plunger H carries a switch finger h², adapted to engage the underside of the elevated end of a terminal arm K, the other end of which extends under the plunger F, said terminal arm being insulated from the base A. In electrical connection with the arm, and directly under the plunger F, is a contact stop L, so that when said plunger is depressed it will be brought into electrical contact with the stop.

Adjacent to the post B, and insulated from the base A, is a binding post J, and leading therefrom to the post d, which, it will be remembered, carries the contact screw D, is a conducting strip j. The latter also extends into electrical connection with the switch terminal K. Adjacent to the binding post

J is another binding post, M, in electrical connection with the base A, and to these binding posts the conductors N, O, are connected, leading to the telegraph line.

5 The operation of the instrument will now be readily understood. If the operator desires to send a dash, or prolonged impulse of current he first opens the circuit by depressing key h' and partially rotating it to carry 10 the finger h² from under the terminal arm K. Upon release of the key the finger h² clears the arm, leaving the circuit open. He then depresses the dash key f', thereby establishing the circuit as follows: wire N, binding 15 post M, base A, bracket E, plunger F, contact stop L, conducting strip j, binding post J, and wire O. Upon release of the key the plunger rises under the influence of spring f, whereupon the circuit is broken at the stop 20 L. If dots, or short impulses of current are to be sent, the key g' is depressed, withdrawing the cam member G' from engagement with the vibrator and causing the latter to oscillate as previously described. When the 25 contact spring C³ strikes the screw D the circuit is established as follows: wire N, binding post M, base A, post B, spring C, vibrator C', spring C³, screw D, post d, conducting strip j, binding post J, and wire O. Then the 30 vibrator immediately swings outward, withdrawing the spring c³ from contact with screw D and thereby breaking the circuit, which, however is reestablished by the succeeding inward swing of the vibrator. In 35 this way the circuit is closed and broken in rapid succession, causing a succession of short impulses, or dots, to be sent over the line. When the desired number of dots have been sent, which the operator ascertains by 40 counting, the dot key, g', is released, whereupon the cam member G is again brought into engagement with the vibrator, arresting it and carrying it out to its inoperative position. Thus by proper manipulation of the 45 dot and dash keys, the dots and dashes of the Morse code can be sent in any number and in any order of succession.

The rate at which the dots are sent is determined by the position of the weight c on 50 the vibrator, the rate being increased by shifting the weight toward the supporting spring C, and vice versa, as will be readily understood.

The finger buttons bear on their tops suitable characters to indicate their functions. Thus on button h' appears the letter "S", indicating switch, the letter being so arranged that when the switch is closed the letter will stand in upright position, as shown 60 in Fig. 4. This position of the letter is assured by the fact that the button cannot be inserted in the plunger H unless the feather i on the button stem is in register with the slot in the plunger. Button g' bears a dot, as 65 shown in Fig. 4, to indicate that it is the dot

key, and button f' bears a dash, not shown, to indicate that it is the dash key.

Users of prior keys of the semi-automatic type have suffered great annoyance through tampering with the adjustments of the device by meddlesome persons. Such persons, seeing the key unused on the operator's table or desk, and attracted by its novelty, stop to examine or test it, and are apt to attempt to readjust it. The consequence is that when 70 the operator tries to use the instrument again he finds the adjustments, to which he has been accustomed, have been disturbed, and he is therefore put to considerable trouble to restore the device to the proper 75 condition for the most effective use. I therefore propose to make the operative parts and the adjusting members inaccessible to the casual passerby and for that purpose I provide a rectangular casing or cover P, to 80 enclose the parts, permitting only the finger keys to project through the cover, through suitable openings therein. To hold the cover or casing securely in place, yet permit removal of the same when desired, the casing 85 is provided with eyes p, Fig. 1, projecting through apertures in the base A, below which they are engaged by suitable hooks a' (shown in dotted lines in Fig. 1) pivoted to the underside of the base. At the rear end of the 90 cover is an opening, indicated in dotted lines at p' in Fig. 1, for the passage of the lead wires N, O. The cover itself is flat, and the entire device is flat and compact enough to enable it to be slipped into the pocket, so 95 that the owner can carry it about with him instead of leaving it on his desk where it may be tampered with by the curious.

The instrument herein specifically described is merely the preferred embodiment 105 of the invention, and may be modified in various ways without departure from the proper spirit and scope of the invention as defined by the appended claims.

What I claim is:

1. In a telegraph transmitter, in combination a base, a horizontally arranged vibrator supported thereon, a vertically reciprocatory plunger having means normally engaging the vibrator and adapted on the downward 115 movement of the plunger to release the vibrator, and a pair of electrical contacts one carried by the vibrator and the other fixed in the path of the first, as set forth.

2. In a telegraph transmitter, in combination, a horizontally arranged vibrator, a blade-spring supporting the same by one end, a contact spring carried by the vibrator, a fixed contact in the path of the contact spring, a vertically reciprocatory plunger 125 adjacent to the free end of the vibrator, and a cam member carried by said plunger adapted to engage the vibrator when the plunger is in its raised position, as set forth.

3. In a telegraph transmitter, in combination,

tion, a horizontally extending vibrator, a dot contact carried thereby, means for connecting the vibrator with one terminal of a telegraph circuit, a vertically reciprocatory plunger adjacent to the free end of the vibrator, and having a cam member normally engaging the vibrator, a second vertically reciprocatory plunger adjacent to the first and in electrical connection with the vibrator, a dash contact adapted to be engaged by the second plunger when the same is depressed, a fixed contact in the path of the dot contact carried by the vibrator, and means for connecting the dash contact and said fixed contact with the other terminal of the telegraph circuit, as set forth.

4. In a telegraph transmitter, in combination, a horizontally arranged vibrator, a spring supporting the same by one end, a bracket extending transversely of the vibrator at its free end, a plunger mounted to reciprocate vertically in said bracket, a cam member carried by said plunger and normally engaging the vibrator, a second plunger mounted to reciprocate vertically in said bracket, a dash contact in the path of the second plunger, a dot-contact carried by the vibrator, and a fixed contact in the path of the said dot-contact, said dash-contact and fixed contact being electrically connected, as set forth.

5. In a telegraph transmitter, in combination, a horizontally arranged vibrator, a dot contact carried by the vibrator, a fixed dot-contact in the path of the movable dot-contact, a series of three vertically reciprocatory plungers extending transversely of the vibrator, means associated with one of said plungers for controlling the vibrator, a fixed dash contact in the path of another of the plungers and in electrical connection with the said fixed contact, and a switch actuated by the third plunger and in circuit with the

vibrator and the said fixed contacts, as set forth.

6. In a telegraph transmitter, in combination, a casing, automatic means within the casing for sending short current impulses in rapid succession over a telegraph line, a vertically reciprocatory plunger controlling said means and extending outside the casing in position for actuation by the finger, a vertically reciprocatory dash-plunger extending outside of said casing, means inside the casing co-operating with said dash-plunger for sending prolonged impulses over the telegraph line when said dash-plunger is depressed, a switch-plunger extending outside of the casing, and a switch inside the casing, operated by the switch plunger for closing and opening the telegraph circuit at will, as set forth.

7. In a telegraph transmitter, a base, a horizontally arranged vibrator supported on the base, means co-operating with the vibrator for sending short current impulses or dots in rapid succession over a telegraph line, a dash-contact mounted on the base and electrically connected with said means, an inclosing casing detachably secured on the base, a vertically reciprocatory plunger to be actuated by the finger of the operator and extending into the casing, means carried by the said plunger within the casing for controlling the vibrator, and a vertically reciprocatory plunger adapted to be actuated by the finger of the operator and adapted to impinge upon the inclosed dash-contact for sending prolonged current impulses or dashes over the telegraph line, as set forth.

In testimony whereof I affix my signature in the presence of two subscribing witnesses.
